SPARK PLUG

Alfred A. St. John, Manchester, N. H.

Application July 10, 1936, Serial No. 89,974

6 Claims. (Cl. 123—169)

My invention relates generally to a spark plug, and particularly to a multiple sparking point spark plug, enabling single, dual, and multiple ignition of a charge in the cylinder of an internal combustion engine, and an important object of my invention is to provide a spark plug of this character which is readily adjustable for single, dual, and multiple ignition, and which is simple and inexpensive in structure.

Other important objects of my invention will be apparent from a reading of the following description taken in connection with the drawings, wherein for purposes of illustration I have shown preferred embodiments of my invention.

15 In the drawings:—

Figure 1 is a general transverse vertical sectional view taken through the embodiment.

Figure 2 is a top plan view of Figure 1 with the inverted U-shaped support removed.

20 Figure 3 is a bottom plan view of Figure 1.

Figure 4 is a transverse vertical sectional view taken through one of the multiplicity of electrodes and showing the cupped formation in its upper end.

25 Figure 5 is a side elevational view of another embodiment of my invention which is provided with an insulated cap adapted to be turned by hand to select the electrodes desired.

Figure 6 is a transverse vertical sectional view 30 taken through Figure 5.

Figure 7 is a horizontal sectional view taken through the upper part of Figure 6 and looking upwardly.

Figure 8 is a perspective view of the brush.

35 Referring in detail to the drawings, the numeral 5 generally designates the embodiment of the invention which comprises a spark plug shell 6 of generally conventional type which involves the exteriorly threaded lower end for engaging the spark plug hole of the engine, with the engine block engaging flange 8 thereabove, and above the flange 8 the wrench receiving flange 9.

In accordance with the present invention the bore of the shell 6 is specially formed to receive 45 the special porcelain or other insulating material core which is generally designated 10 and which comprises the plain upper cylindrical portion 11, the lower plain cylindrical portion 12 and the triangular cross section flange 13 intermediate the

50 portions 11 and 12 and which engages on a curved shoulder 14 at the upper end of the plain bore portion 15 of the shell 6. The upper extremity of the bore of the shell 6 is enlarged in diameter and interiorly threaded as indicated by the numeral 55 16; and threaded into the upper end of the bore

is the core locking nut 16 which engages the threads 15 and also the top of the triangular cross section shown at 13 of the core, whereby the core is locked in place in the shell 6. It is to be observed that the core 10 does not rise above the shell 6 to as great a height as is conventional.

The core is provided on its upper end with a reduced portion 17 which receives the dielectric cap 18 which seats on the reduced portion and flush with the exterior of the core.

Depending through the middle of the cap 18 is the binding post 19 which has its lower end anchored as indicated by the numeral 20 in the top of the core, and has its upper end threaded as indicated by the numeral 21 to receive the binding post nut 22 which clamps the spark plug wire clip or connector to my spark plug.

Close to the exterior of the core 10 is a series of equally circumferentially spaced longitudinal electrodes 23 which have enlarged upper ends 24 provided with cupped portions 25, the ends 24 being flush with the upper end of the core; and the lower ends of the electrodes being exposed below the bottom of the core and on a level with the depending portion 26 which has radial slots 27 therein which open through the sides of the electrodes and form sparking chambers in such a way that adjacent electrodes are isolated from each other so that there can be no jumping across of a spark between adjacent or opposite electrodes.

The lower end of the shell 6 is disposed on a level with the bottom of the core and has depending therefrom the L-shaped sparking points 28 which have their horizontal arms radially inwardly directed and properly spaced from the lower ends of the electrodes 23, as clearly shown in Figure 3.

Pivoted on the binding post 19 are the inner ends of one or more contact arms 29, 30 which have contact buttons on the underside of their outer ends to seat in the depressions 25 in the upper ends of the selected electrodes 23. With the spring contact arms 29 and 30 arranged as shown in Figure 2, dual ignition is conditioned. Any number of arms may be utilized up to the full total number of the electrodes in the core; or only one of the contact arms may be utilized to obtain single ignition.

A helical spring 31 interposed between the cap 18 and the tops of the arms 29 and 30 retain the arms in forcible contact with the upper ends of the electrodes 23.

The embodiment of the invention shown in Figures 5, 6, 7, and 8 of the drawings has the same

shell, core, electrodes, and the same core locking nut, as well as the same formations and arrangements of the electrodes and core and shell at the lower end of these. Therefore corresponding numerals, primed, have been applied to designate these similar parts in Figures 5, 6, 7, and 8 of the drawings.

In addition to the parts mentioned above the present embodiment has flanges 32 on the electrodes 23' embedded in the material of the core to prevent shifting of the electrodes.

The tops 33 of the electrodes are here convex instead of concave and they are engaged selectively by a convex portion 34 on the outer extremity of the spring arm 35 which extends radially from the collar 36 which turns on the binding post 20'. In the present instance anchoring flanges 37 are formed on the lower part of the binding post.

20 The collar 36 is fastened rigidly by suitable means 38 to the bottom of a hollow dielectric cap 39 which is rotatable on the binding post 19' and may rest on the upper end of the nut 16'. Simply turning the dielectric cap 39 rings the contact arm 35 into engagement with the selected one of the electrodes 23.

On the threaded upper end of the binding post a suitable spark plug wire connection 40 is threaded and holds the cap 39 in place.

30 Although I have shown and described herein preferred embodiments of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. A spark plug of the character described comprising a spark plug shell having a plurality of circumferentially spaced sparking points on its lower end, a core mounted in the shell and having a plurality of circumferentially spaced electrodes extending longitudinally therethrough, said core being formed with protective openings in the lower end thereof in which said electrodes project adjacent corresponding ones of the sparking points, and adjustable contact means on the upper end of the core in conjunction with a binding post for selectively energizing different ones of the electrodes simultaneously.

2. A spark plug of the character described comprising a spark plug shell having a plurality of circumferentially spaced sparking points on its lower end, a core mounted in the shell and having a plurality of circumferentially spaced electrodes extending longitudinally therethrough, said core being formed with protective openings in the lower end thereof in which said electrodes project adjacent corresponding ones of the sparking points, adjustable contact means on the upper end of the core in conjunction with a binding post for selectively energizing different ones of the electrodes simultaneously, said adjustable contact means comprising a dielectric rotatable cap on the upper end of said core, and a spring brush fixed thereto for selectively engaging the upper ends of the electrodes.

3. A spark plug of the character described comprising a spark plug shell having a plurality of circumferentially spaced sparking points on its lower end, a core mounted in the shell and having

a plurality of circumferentially spaced electrodes extending longitudinally therethrough, the lower end of said core being formed with protective openings in which said electrodes project adjacent corresponding ones of the sparking points, and adjustable contact means on the upper end of the core in conjunction with a binding post for selectively energizing different ones of the electrodes simultaneously, said adjustable contact means comprising swingable spring arms pivoted in the axis of said core and selectively engageable with different ones of the upper ends of said electrodes simultaneously.

4. A spark plug of the class described comprising a spark plug shell having a plurality of circumferentially spaced integral L-shaped sparking points on its lower end, a core mounted in the shell and provided with a plurality of circumferentially spaced electrodes extending longitudinally therethrough, the electrodes being wholly spaced radially inwards of the peripheral outer surface of said core and having the upper and lower ends exposed through the corresponding ends of said core, the lower ends of said electrodes being cooperable with adjacent sparking points, a binding post operatively associated with the upper end of said core, and adjustable contact means on the upper end of the core cooperable with the binding post, said contact means including a rotary arm, said arm being disposed radially with respect to the adjacent end of the core, and having its outer end terminating within the diameter of the core and selectively engageable with different ones of the electrodes.

5. A spark plug of the class described comprising a shell, a core mounted in said shell, said shell being provided on its lower end with a plurality of circumferentially spaced contact points, a plurality of circumferentially spaced electrodes extending longitudinally through said core having their lower ends exposed through the lower end of the core for coaction with said contact points, the upper ends of said electrodes terminating flush with the upper end of the core, a binding post secured centrally to and rising from the upper end of said core, a retention nut on said binding post, a protective cap of insulation material surrounding the binding post and interposed between the adjacent end of the shell and nut, and a radial conductive arm swingable on the axis of said binding post and attached to said cap for rotation therewith, the outer end of said arm being resilient and terminating within the limits of the diameter of the adjacent end of the core and being selectively engageable with the adjacent ends of said electrodes.

6. A spark plug of the class described comprising a shell, a core mounted in said shell, a plurality of electrodes extending longitudinally through said core and exposed at their upper and lower ends, a binding post mounted on top of said core, said binding post including clamping nut, a pair of duplicate selectively and collectively operable conductive arms pivotally attached at corresponding inner ends to said binding post, the outer ends of said arms being adapted for selective engagement with the adjacent ends of said electrodes, and spring means associated with the binding post to maintain the arms in yieldable engagement with the electrodes.
